Primary Examiner — Khawaja Anwar(74) *Attorney, Agent, or Firm* — Barnes & Thornburg LLP(57) **CLAIM**

The ornamental design for a chamfered-edge plate with notches and center aperture, as shown and described.

DESCRIPTION

FIG. 1 is a top front perspective view of the chamfered-edge plate with notches and center aperture;

FIG. 2 is a top rear perspective plan view thereof;

FIG. 3 is a front elevation view thereof;

FIG. 4 is a rear elevation view thereof;

FIG. 5 is a left side edge view thereof;

FIG. 6 is a right side edge view thereof;

FIG. 7 is a top side edge view thereof; and,

FIG. 8 is a bottom side edge view thereof.

The broken lines in the drawings shown environment and form no part of the claimed design.

1 Claim, 5 Drawing Sheets(56)
